UNITED STATES PATENT OFFICE.

GEORGE WEDDERBURN, OF DUNN LORING, VIRGINIA.

CARBURETING-LAMP.

SPECIFICATION forming part of Letters Patent No. 707,190, dated August 19, 1902.

Application filed November 8, 1901. Serial No. 81,542. (No model.)

To all whom it may concern:

Be it known that I, GEORGE WEDDERBURN, a citizen of the United States, residing at Dunn Loring, in the county of Fairfax and State of Virginia, have invented certain new and useful Improvements in Lighting Devices; and I do hereby declare the following to be a full, clear, and exact description of the invention, such as will enable others skilled in the art to 10 which it appertains to make and use the same.

This invention relates to lighting devices, and although designed primarily for street-lighting it is evident that the same may be used for house-lighting and other purposes, 15 and hence I do not wish to be limited to any particular use of the invention.

The broad principle of the invention consists of a burner so constructed as not to admit any air into the interior of the chimney 20 or globe, so that when heat is produced in the burner an exhaustion of the air is caused therein by virtue of the heat ascending through a flue communicating with the top of the globe or chimney, and to relieve this 25 exhaustion air enters through perforations in the oil-receptacle or the inclosure for the wick and in its passage over the wick is transformed into gas, which passes on up through the tube to relieve the pressure in 30 the globe and continues to burn. The principle thus briefly outlined is capable of embodiment in a variety of forms, some only of which I have chosen to herein illustrate; but I do not intend to restrict myself to these particular forms, which are given merely as 35 illustrations of practical means for carrying out the invention, which in its broad sense comprehends the use of a vacuum for lifting the gas from the generator to the point of ignition.

Other objects and advantages of the invention will hereinafter appear, and the novel features thereof will be specifically defined by the appended claims; but it may be here 45 added that my invention permits of the production of a very bright light at a minimum cost and the structural embodiment of the invention entails but small cost, the device being simple in its nature, of few parts, and 50 those readily assembled and not liable to get out of order.

By my invention I am enabled to provide a cheap light for use in the country for lighting the streets without the expense of the construction of a plant, the running of pipes 55 for gas, or the maintenance of such a plant, and the lights are portable, and hence can be placed where desired.

The invention in its preferable forms is clearly illustrated in the accompanying drawings, which, with the numerals of reference marked thereon, form a part of this specification, and in which—

Figure 1 is an elevation with portions broken away and parts in section showing 65 the application of one form of the invention. Fig. 2 is a vertical section, with parts in elevation, of another form of the invention. Fig. 3 is a detail in perspective showing the gauze cap on the upper end of the tube. Fig. 70 4 is a cross-section on the line 4-4 of Fig. 1 looking down.

Like numerals of reference indicate like parts throughout the several views.

Referring now to the details of the drawings, 75 1 designates a lamp-post, and 2 a continuation thereof forming a base. Within this base is a box or receptacle 3, within which is disposed the cone-shaped wall 4, terminating in the point 5.

6 is a filling-tube or the like through which the oil may be admitted into the receptacle 3.

7 is a wick fitted over the cone-shaped wall 4, as shown in Fig. 1, and over this wick and supported upon the top of the receptacle 3 is 85 a covering 8, having near its lower end the perforations 9. This covering has a neck portion 9^a, over which is fitted the lower end of the tube 10, which extends upward through the post, as seen clearly in Fig. 1.

90 11 is a gauze cap on the upper end of the tube 10 for distributing the flame.

12 is a support for a mantle 13 of any approved forms of construction, which mantle is disposed over the upper end of the tube 10, 95 as seen clearly in Fig. 1.

14 is a plate or disk secured to the upper end of the lamp-post, as shown, and this plate snugly embraces the tube 10, and upon its upper face it is provided with a recess or depression 14^b, in which is disposed a rubber or analogous collar or packing 14^a, upon which

rests the lower end of the half-globe 15, the construction being such as to prevent the outside air from entering the half-globe through its bottom portion.

5 16 is the upper half-globe, which rests upon the top of the lower half 15, and the fit between the two at their meeting-points is designed to be air-tight, so as to prevent the ingress of air at this point, and to insure this 10 I provide a rubber or analogous collar or packing-ring 17, as seen in Fig. 1.

15 18 is a flue which is supported removably and adjustably in the upper half of the globe, as by the set-screw 18^a. This flue extends down within the globe the required distance and may be elevated when the mantle is to be inserted and afterward lowered and securely held in its proper position. Any suitable means may be provided for gaining access to 20 the base 2.

25 In operation the gasoline is placed in the receptacle 3, and the wick being in place, as shown, so that its lower portion is immersed in the oil or gasoline, the air in passing in through the perforations 9, coming in contact with the wick and the oil therein, gas is generated, and the gas thus generated will be immediately sucked up through the tube 10 and will pass through the wire-gauze cap 11 in 30 the form of gas, where it is ignited in any suitable way. I thus obtain a very bright and steady light, the gas being drawn up from the generator by means of the exhaustion of the air formed in the globe by the heat therein. The lamp is started in any suitable way—for instance, by dropping an ignited piece of sponge or any other absorbent material saturated with gasoline or other material into the top of the tube 18.

35 40 In Fig. 2 I have shown another arrangement for generating the gas. In this form there is located within the base 2 a box 19, having an opening 20 to receive the lower end of the gas-tube 21, which receives the lower 45 end of the tube 10. 22 represents openings in the top of the box near one end for the admission of air, and near the other end of the said box or receptacle is an opening 23 to receive the lower end of the pipe 25, which within 50 in the box 19 has perforations 24, as shown. This tube 25 extends from the gasoline tank or receptacle 26, preferably located within the base, although it is evident that it may be located in any other desired position.

55 55 The operation is as follows: The fluid passes through the pipe 25 and its perforations 24 until the latter are closed by the fluid rising in the tank 19 to a sufficient height, and when the fluid in the said tank falls below the perforations fluid from the tank 26 will again flow into the tank 19. The construction is such as to give as much surface on the fluid as possible, so that when the air is admitted through the perforations 22 in the top of the 60 box it will pass over and through as much of the surface of the fluid as possible, and thus 65

create the greatest amount of evaporation, and thus generate the gas, which passes up through the tubes 21 and 10 and through the wire-gauze 11, where it is burned within the 70 globe as before. In both instances when heat is produced in the burner an exhaustion is caused therein by virtue of the heat ascending through the tube or flue 18 and the air rushing through the perforations 9 in 75 Fig. 1 to relieve the pressure caused by said exhaustion, and in its passage over the wick it is transformed into gas, and the pressure being relieved thereby as it enters the globe the gas will continue to burn with a bright 80 and steady flame.

85 From the above it will be evident that I have devised a novel construction of lamp, and while the structural embodiment of the principle of the invention as herein disclosed 90 is what I at the present time consider the preferable it is evident that the same is subject to changes, variations, and modifications without departing from the spirit of the invention or sacrificing any of its advantages, 95 and I therefore do not wish to be restricted to the details herein illustrated, but reserve the right to make such changes, variations, and modifications as come properly within the scope of the protection prayed. 95

What I claim as new is—

1. A lamp embodying a fluid-receptacle, a tube leading therefrom to the point of ignition, a globe closed at its lower end, a burner in said globe, and means for generating gas 100 by the exhaustion of the air in the globe by the ignition of the burner and drawing the same upward from the generator to the point of ignition.

2. A lamp embodying a fluid-receptacle, a 105 tube leading therefrom to the point of ignition, a globe inclosing the upper end of said tube and closed at all points except its upper end, a flue leading from the upper portion of the globe, and means for generating gas by 110 exhaustion created in the globe when the lamp is ignited.

3. A lamp embodying a fluid-receptacle below the point of ignition, a tube leading therefrom to the point of ignition, a globe inclosing the upper end of the said tube, means for creating an exhaustion in said globe when the lamp is ignited and for drawing the generated gas upward through said tube to the point of ignition within the globe. 115 120

4. A lamp comprising a fluid-receptacle located at a point below the point of ignition, a globe, a tube leading from the said receptacle and terminating within said globe, and means for drawing air into said receptacle 125 over the fluid therein and up through the said tube and into the globe upon the ignition of the lamp.

5. A lamp comprising a fluid-receptacle below the point of ignition, a globe above said 130 receptacle, a tube leading from the receptacle to the globe, means for admitting air to

the receptacle over the surface of the fluid therein to evaporate the latter, means for generating gas by exhaustion created in the globe when the lamp is ignited, a tube leading from 5 the top of the globe, and a mantle over the upper end of the first-mentioned tube within the globe.

In testimony whereof I affix my signature in presence of two witnesses.

GEORGE WEDDERBURN.
